UNITED STATES PATENT OFFICE.

THOMAS B. HENNESSY, OF CHICAGO, ILLINOIS, ASSIGNOR, BY MESNE ASSIGNMENTS, TO THE EMBALMER'S SUPPLY COMPANY, OF WEST-PORT, CONNECTICUT, A CORPORATION OF NEW JERSEY.

EMBALMER'S TABLE.

SPECIFICATION forming part of Letters Patent No. 723,605, dated March 24, 1903.

Application filed July 24, 1901. Renewed January 15, 1903. Serial No. 139,164. (No model.)

To all whom it may concern:

Be it known that I, THOMAS B. HENNESSY, a citizen of the United States, and a resident of Chicago, in the county of Cook and State of Illinois, have invented certain new and useful Improvements in Embalmers' Tables, of which the following is a full, clear, and exact specification.

In embalming it is desirable to turn the subject operated on in different positions during the process.

This invention relates to an embalmer's table which is adjustable in height and angular position and is provided with means for changing its position when under load.

The invention consists of the matters hereinafter set forth, and more particularly pointed out in the claims.

In the drawings, Figure 1 is a view in side elevation of a table embodying the features of my invention. Fig. 2 is a view in central vertical section through the table. Fig. 3 is plan view of the clamping-block. Fig. 4 is a side view of the clamping-block. Fig. 5 is a central section through the clamping-bolt washer, showing a portion of its curved shank.

Referring to the drawings, A represents a rectangular table-top or drainage-slab on which the subject to be operated on is laid. This slab is provided with a rim a and is slightly dished, so that any liquid striking its surface will flow to one or the other of two drain-openings a', which are located near either end of the slab. The slab is mounted on two parallel segmental brackets B, secured by bolts b or other suitable means to the under side of the slab near its margins and at its center of length. These brackets comprise separated concentric segments and swing in a U-shaped yoke C', being pivoted to the ends of the upwardly-projecting yoke-arms c on pintles D, which pass through the radial centers of the slots E, formed by the separated segments. These centers are preferably close to the slab, so as to bring its center of gravity when loaded as near as possible to its center of oscillation. This yoke C', on which the brackets may be clamped at any desired angle by means hereinafter described, is carried by a supporting-post F, whose upper

end is centrally secured to the cross-arm c' of the yoke. Said post is revoluble in the central boss g of a standard or base G of any preferred design. It may be raised or lowered therein by means of a hand-wheel H, 55 whose hub h has screw-threaded engagement with the supporting-post F and rests or bears on the upper end of the boss g.

To clamp the brackets and yoke together, a bolt I is provided, which may be rotated by 60 a handle-bar J, secured to one end thereof. This bolt passes through suitable apertures in the yoke-arms c and through the slots E of the brackets. Near its headed end remote from the handle-bar it passes through a non-rotatable washer K, which has a tenon k, engaging and traveling in the slot E of the adjacent bracket. Near the handle it passes through a non-rotatable clamping-block L, provided with a projection l, which enters 70 and travels in the slot C of the proximate bracket. The face of the block L contiguous to the handle-bar J has two oblique cam-surfaces l', which engage two similar cams j on the boss-face of the handle J. When the latter is turned in the proper direction, it securely and quickly locks the parts together. 75

The table can be quickly raised or lowered with a minimum of effort by the hand-wheel. It is free to turn in either direction, and can 80 be tilted at any angle desired and secured there to suit the needs of the operator. It is sufficiently rigid to move freely under a load without binding. Owing to the proximity of the centers of gravity and oscillation, 85 it requires but slight outlay of power to tilt the slab, and when adjusted it is stable. The contour of the slab affords perfect drainage.

The mechanical details may obviously be varied without departing from the spirit of 90 the invention, and I do not limit myself to any specific construction save as set forth in the appended claims.

What I claim as new is—

1. An embalmer's table, comprising a suitable slab, corresponding parallel brackets secured longitudinally to the under side of said slab, about midway its length and each provided with two concentric segments, a suitable stand, a threaded supporting-post ver- 95 100

- tically adjustable in the central opening of said stand having a yoke made integral with its upper end, a hand-wheel having an interiorly-threaded boss engaging said post, a pintle pivotally connecting said brackets to the ends of the arms of said yoke at points coinciding with the centers of the segments thereof, a clamping-bolt extending through the slot between the two segments of each bracket and provided with a suitable head on one end and a handle or lever for turning it on the other, a non-rotatable washer on the head of the end of said bolt and a non-rotatable clamping-block on the other end thereof next said handle, said clamping-block and the face of the boss of the handle engaging the same having cam-surfaces whereby when said bolt is turned said washer and said clamping-block clamp said brackets to said yoke.
- 20 2. An embalmer's table comprising a suitable slab, corresponding parallel brackets secured longitudinally to the under side thereof about midway its length and each provided with two concentric segments, a suitable stand, a threaded supporting-post vertically adjustable in the central opening there-
- of, having a yoke made integral with its upper end, a hand-wheel having an interiorly-threaded boss engaging said post, a pintle pivotally securing said brackets to the arms of said yoke at points coinciding with the centers of the segments thereof, a bolt extending through the lower ends of the arms of said yoke having its ends extended through the slots between the segments of each bracket and provided with a head on one end a handle for turning it at the other, a flanged washer on said bolt next its headed end having a flattened extension extending between the segments of the adjacent bracket, and a clamping-block on the other end of said bolt having a flattened extension extending between the segments of the opposite bracket, the outer face of said clamping-block and the side of the boss of the handle engaging the same having cam-surfaces, whereby when said bolt is turned the brackets are clamped against the arms of said yoke.

THOMAS B. HENNESSY.
